The ornamental design for a reflective license plate frame, as shown and described.

DESCRIPTION

FIG. 1 is a front elevational view of a reflective license plate frame.

FIG. 2 is a top view thereof, the bottom view being a mirror image.

FIG. 3 is a left end view thereof, the right end view being a mirror image.

FIG. 4 is a rear elevational view thereof; and

FIG. 5 is a front perspective view thereof, showing one of the four snap in reflective bolt covers removed.
